Patented Sept. 21, 1971

221,991

TURF VACUUMING DEVICE

William S. Jensen, Rolling Hills Estates, Calif., assignor
to Turf-Vac Corporation, Long Beach, Calif.

Filed Jan. 26, 1970, Ser. No. 21,097

Term of patent 14 years

Int. Cl. D15—06
U.S. Cl. D49—9.1

FIG. 1 is a perspective view of a turf vacuuming device showing my new design;

FIG. 2 is a side elevational view thereof; and

FIG. 3 is a rear elevational view thereof.

I claim:

The ornamental design for a turf vacuuming device, substantially as shown.
